ELECTRIC GRILL

Herbert R. Carpenter, Chicago, Ill., assignor to
Dominion Electric Corporation

Filed June 25, 1962, Ser. No. 70,665

Term of patent 14 years

(Cl. D81—10)

FIG. 1

FIG. 2

FIG.3

FIG.4

FIGURE 1 is a perspective view looking downwardly from the front of the grill;

FIGURE 2 is a perspective view looking downwardly from the rear of the grill;

FIGURE 3 is an enlarged end view looking at the right hand end of the grill shown in FIGURE 1; and

FIGURE 4 is an enlarged bottom view looking upward on the bottom of the grill shown in FIGURE 1.

I claim:

The ornamental design for an electric grill, substantially as shown.
